UNITED STATES PATENT OFFICE

FRANK B. BELL, OF PITTSBURGH, PENNSYLVANIA, ASSIGNOR TO EDGEWATER STEEL COMPANY, OF PITTSBURGH, PENNSYLVANIA, A CORPORATION OF PENNSYLVANIA

METHOD OF FORMING CAR WHEELS

Application filed September 26, 1935. Serial No. 58,724.

This invention relates in general to wheels, and more particularly to wheels of the dished type adapted for use on railway cars and the like, and has for an object the provision of such a device that will be free from internal strains, such as may cause breakage of the wheel under operating conditions and temperatures. In wheels of this type provided heretofore, the dished portion has been formed by pressing the hub and some of the metal of the dished portion to one side to form the dish, and in forming the dish after this fashion, various unequal internal strains are set up in the metal as an incident to the operation. These strains at times approach very closely to the limit of the strength of the metal and produce faulty wheels, which, when put into service will crack or break at the point of strain. In wheels formed in accordance with this invention, such strains are not present and, therefore, this breakage does not occur and a stronger wheel is produced having greater lasting qualities.

Another important object is to provide a method of forming such a device that will eliminate or reduce unequal internal strains.

Numerous other objects and advantages of the invention will be apparent as it is better understood from the following description, which, taken in connection with the accompanying drawings, discloses a preferred embodiment thereof.

Referring to the drawings,

Figure 1 is a plan view illustrating a method of forming a wheel in accordance with my invention;

Figure 2 is a section taken substantially on line 2-2 of Figure 1 showing a wheel at the beginning of the rolling operation;

Figure 3 is a similar view showing the wheel finished;

Figure 4 is a view of a wheel block for forming the wheel;

Figure 5 is a sectional view of a forging die showing a wheel after the first forging operation;

Figure 6 is a sectional view of a wheel as further formed; and

Figure 7 is a similar view of a wheel fully formed.

I have shown on the drawings various steps for producing a wheel in accordance with my invention.

Figure 4 indicates a metal block before any operations are performed. Figure 5 shows the block 11 after a preliminary forging operation and in position between forging dies 16 and 17. Figure 6 discloses the same block as further formed and in fully formed condition except that a hub portion 13 of the wheel and a web portion 14 may be pressed in a reversed direction to the position shown in dotted lines to eliminate strains in the web portion 14, such as may be caused in the preliminary forging operation. While it is not essential that the preliminary dishing be accomplished in the first forging operation, it is preferable to dish the blank at this operation. The forging dies 16 and 17 may be mounted in any suitable press, and a centering pin 18 is preferably provided in these dies to centrally locate the blank.

While forming rolls of any suitable shape may be used, I have shown (Figures 1 and 2) the wheel blank 15 clamped between a plurality of idler forming rolls 21 and a driving and forming roll 22 of a rolling machine and a pair of oppositely disposed forming rolls 23 which may be suitably supported and controlled by shafts 24, the rolls 21 and 22 being adapted to form the periphery or tread of a wheel, and the wheels 23 being adapted to extend the rim to form the side and inner portions thereof and to form a further dished web portion to produce a finished dished wheel 25 (Figure 3) of larger diameter.

Dishing the web beyond the operative position and then returning it to operative position to equalize internal strains as above described may be accomplished in any suitable manner such as above described or by pressing beyond and rolling back to operative position, or by rolling beyond and back to operative position, or the like.

The preferred manner of carrying out the new and improved process here sought to be patented is to complete the rolling of the car wheel with a dish more than desired in the finished wheel and thereafter reducing the amount of this dish in the usual dishing

and hub centering press heretofore well known to all skilled in the art. This manner of practicing the process is fully apparent, it is believed, from the foregoing.

5 It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

10 15 I claim:

1. A method of forming dished car wheels, which consists in forming a wheel having a web portion and bending said web portion first in one direction and then in a reverse direction to dish form.

20 2. A method of forming dished car wheels, which consists in forming a wheel blank having a hub portion, a rim portion and a dished web portion connecting said hub and said rim portions, and rolling said wheel blank into a wheel of similar form of a larger diameter and to vary the dished web portion.

25 3. A method of forming dished car wheels, which consists in forging a wheel blank having a hub portion, a rim portion and a dished web portion connecting said hub and rim portions and having a greater convexity than the finished wheel, and rolling said wheel blank into a finished wheel by forming a flange and tyre from said rim portion and reducing the convexity of said web portion in order to minimize the stresses caused by forming the dished web in the blank.

30 4. A method of forming car wheels, which comprises rolling a car wheel to final diameter and with a dished web part connecting the hub and rim, the dish of which is greater than that desired in the finished wheel, and thereafter reducing the dish of said web part.

45 5. The method of forming dished car wheels, which comprises forming a car wheel with a dished portion distorted from its normal dished contour in the finished wheel, and thereafter by a further wheel forming operation restoring the dished portion of the wheel to its normal contour.

FRANK B. BELL.
